UNITED STATES PATENT OFFICE.

ALVAH WISWALL, OF CINCINNATI, OHIO, ASSIGNOR OF ONE-HALF TO
MATTHEW BRITTON, OF SAME PLACE.

PROTECTING DEVICE FOR BANK-SAFES.

SPECIFICATION forming part of Letters Patent No. 286,566, dated October 9, 1883.

Application filed July 14, 1883. (No model.)

To all whom it may concern:

Be it known that I, ALVAH WISWALL, a citizen of the United States, residing at Cincinnati, in the county of Hamilton and State 5 of Ohio, have invented certain new and useful Improvements in Protecting Devices for Bank-Safes, &c., of which the following is a specification.

My invention is an improvement on those 10 devices whereby the opening or disturbance of a door or other object placed for protection of valuables is made known at a distant station by an audible or other signal or "alarm" put in motion through the medium of an electro-magnetic connection with such object.

My improvement consists, essentially, in the provision of two distinct circuits, of which each has electrical communication with a separate electro-magnetic signal of any suitable or 20 customary construction. One of these circuits (which is closed when set) operates an alarm by having its continuity broken. The other circuit (which is open when set) operates an alarm by having its continuity restored.

Such association of two distinct circuits working in diverse fashion constitutes a double safeguard that operates with various manifestations to indicate whatever clandestine attempt 25 is made at disturbance of the guarded object, and which advertises the very character of the disturbance.

In the accompanying drawings, Figure 1 is a partly-sectional diagrammatic representation of an apparatus embodying my invention, the same being shown in its set condition. Fig. 2 represents the circuit-changing mechanism in its discharged condition. Fig. 3 is a transverse section at the line *x x*. Fig. 4 represents the device adapted for use in connection with 40 more than one object. Fig. 5 shows the form used when the circuit-changer is at right angles to the movement of the protecting object.

A is a non-metallic tube, sheath, or housing, which is made fast to the safe body or casing, 45 so as to present it at right angles and in near proximity to the door *B* or other protecting object.

Attached interiorly to the tube *A* is a rod, *C*, of brass or other metal, to whose rear end

is attached a wire, *D*. This rod *C* is enveloped by a sleeve, *E*, of vulcanite or other insulating substance, a spring, *F*, attached to which holds a metallic rod, *C'*, similar to the rod *C*. Said rod *C'* is held by said spring *F* normally out of contact with said rod *C*. Attached to the front end of rod *C'* is a non-metallic push piece or button, *G*. From the rod *C'* proceeds a wire, *D'*. The rods *C C'* constitute the terminals of an electro-magnetic circuit containing one or more voltaic batteries, (see 60 broken lines in Fig. 1,) whose rupture (by the separation of said rods *C C'*) operates to sound an alarm, *Y*, with which the wires *D D'* communicate. Embracing the sleeve *E* and made fast to it is a metallic band, *H*, to which is attached a wire, *J*. Also embracing said sleeve, but capable of sliding freely along it, is a similar band, *H'*, which has rigid but insulated connection *K* with the rod *C'* through the push-piece *G*. Proceeding from the band *H'* is a 70 wire, *J'*. The bands *H H'* constitute the terminals of an electro-magnetic circuit, whose closure (by the contact of said bands) operates to sound an alarm, *Z*, with which the wires *J J'* communicate. All the four wires *D D' J J'* 75 are wrapped with insulating material, and all (for compactness, and to make it difficult to tamper with them) are, wherever exposed to view, preferably twisted into cable form, as shown in Fig. 1.

The above-described duplex circuit-changer is so located upon the safe or other receptacle to be protected that closure of the door *B* operates to bring into juxtaposition the opposing ends of the rods *C C'*, and to thus, for the 85 time being, close the circuit *C D Y D' C'*, while at the same time (by separating the bands *H H'*) to open, for the time being, the circuit *H J Z J' H'*. This "set" condition of the parts is shown in Fig. 1. The act of opening the door 90 *B* relieves the push-piece *G* and permits the mechanism to resume the condition shown in Fig. 2. Such movement causes both alarms to sound, and, by both sounding, to advertise to the person in charge the special nature of 95 the intrusion. Should the trespasser, on the other hand, resort to the expedient of cutting the wires, he will only the more distinctly give

information of the intrusion (by sounding the alarm Y only) of the closed circuit. Should he, on the contrary, attempt to cut out or shunt the protected safe by connecting its wires to 5 "line" beyond the safe, he will equally fail of his purpose, because such act (by baring adjacent portions of the wires J J of the open circuit) will make communication between them, and will give information (by sounding 10 the alarm Z only) of the exact nature of the disturbance. It is thus manifest that several different kinds of intrusion are not only equally sure to communicate information of disturbance, but to particularize in what that disturbance 15 consists.

For use with two or more protecting objects—such, for example, as a safe-door and a money-drawer, B', (see Figs. 4 and 5)—the terminal mechanism above described is repeated 20 at the additional object. In such use of the device the circuit which is closed when set is connected in series, as follows: The wire D of the circuit C D Y D' C', communicating with the rear rod, C, of one pair of terminals, the opposing rod, C', of the same pair communicates, 25 by wire d, with the rear end of rod C of the next pair, and so on for as many terminal mechanisms as there are protecting objects, the return-wire D' being connected to the rod C' of the last terminal pair of the series. At the same 30 time that the closed circuit is thus connected in series, the open circuit is connected in multiple arrangement by addition of branch wires j j' to the corresponding terminals of the added 35 contact-changer.

I claim as new and of my invention—

1. In an electro-magnetic safe-protecting device, the two pairs of terminals C C' and H H', having separate electrical connection with as many signal circuits or systems, adapted to 40 act simultaneously—the one by opening and the other by closure—by movement of the safe-door or other protecting object, substantially as set forth.

2. In an electro-magnetic safe-protector, the 45 combination, with as many distinct alarms of the duplex terminal mechanism of which one part consists of normally-separated rods C C', that constitute the terminals of one alarm system, and that, when set, form part of a closed 50 circuit that operates to sound the alarm on being opened, and of which the other part consists of normally-closed bands H H', that embrace rod C, (from which they are insulated,) which bands constitute the terminals of the other 55 alarm system, and, when set, form part of an open circuit that operates to sound the alarm on being closed, substantially as set forth.

3. In an electro-magnetic safe-protector, the 60 duplex circuit opener and closer, consisting of the fixed terminals C and H, the shifting terminals C' and H', insulating-sleeve E, spring F, non-metallic push-piece G, and the rigid connection K, the whole being inclosed in a 65 non-metallic attachment sheath or housing, A, substantially as set forth.

In testimony of which invention I hereunto set my hand.

ALVAH WISWALL.
